CONSTANT DELIVERY VANE PUMP

Warren R. Tucker, Dayton, Ohio, assignor to The
Hydraulic Development Corp. Inc., Wilming-
ton, Del., a corporation of Delaware

Application December 22, 1939, Serial No. 310,508

12 Claims. (Cl. 103—121)

This invention relates to a constant delivery vane pump and more particularly to such a vane pump in which the cylinder or ring which the vanes contact is freely rotatable and therefore rotates with the rotor and vanes at substantially the same speed as that imparted to the rotor and vanes.

It is, accordingly, an object of the present invention to provide a constant delivery or displacement vane pump in which the cylinder or ring is carried rotatably with the rotor.

It is a further object of the present invention to provide a constant delivery pump wherein two members (commonly circular), one of which surrounds the other, are fixedly positioned eccentrically with respect to one another, wherein vanes carried by one of the members extend between these two members and form pumping chambers therebetween, and wherein both of the members are freely rotatable; power is applied to (or taken off from in the case where the pump is operated as a motor, being supplied with fluid under pressure) that member which carries the vanes.

It is a still further object to provide a constant delivery vane type pump of the foregoing type wherein the member which the vanes engage is rendered freely rotatable by its disposition as one race of an anti-friction bearing such as a roller or ball bearing.

It is another object to provide for porting and valving of a vane pump of the foregoing type whereby a useful pump is obtained.

It is another object of this invention to provide a complete assembly of rotor, the bearing assembly on the outside of said rotor and the distribution sleeve, all of which move together and can be adjusted together within the casing, longitudinally of the casing, to accommodate wear and slight movement in operation. In this manner, the pump is self-accommodating in its moving parts to varied conditions of operation and to wear. Additionally, means is provided for adjusting the supporting bearings for this complete assembly and for simultaneously moving the rotor, its bearing assembly and the distribution sleeve together so that one adjustment will adjust all of the operating parts for wear.

It is a further object of this invention to provide bearings for supporting the shaft of the pump rotor, which bearings support the distribution sleeve in such a manner that the total diameter of the bearings is sufficient to support the distribution sleeve in spaced relationship to the casing with a sufficient clearance that any bend-

ing moment of the rotor shaft and of the distribution sleeve will not cause any binding between the sleeve and the pump casing, but at the same time the clearance is so small that a substantially fluid-tight engagement is maintained, particularly when pumping fluids such as oil, where the viscosity of the oil in combination with the slight clearance provided is sufficient to make a substantially fluid-tight seal and to lubricate the rotating distribution sleeve as it turns within the casing.

Still other objects will more fully hereinafter appear as the detailed description of one embodiment of the present invention proceeds.

15 In the accompanying drawings:

Fig. 1 is a vertical longitudinal section through a pump embodying the principles of the present invention, taken on the line 1—1 of Fig. 2, looking in the direction of the arrows.

20 Fig. 2 is a vertical transverse section taken on the line 2—2 of Fig. 1, looking in the direction of the arrows.

Fig. 3 is a vertical transverse section taken on the line 3—3 of Fig. 1, looking in the direction of the arrows.

25 Fig. 4 is an enlarged fragmentary view, similar to Fig. 1, with the clearances between several of the parts greatly exaggerated for clarity.

In this specification and in the claims appended 30 hereto, while the term "pump" will be employed, this term is to be understood as including either a pump in the true sense or a fluid motor since the device described herein may be employed as a pump by applying power to turn the rotor, or as 35 a motor by supplying fluid under pressure to the device. It is also to be understood that while a hydraulic pump is described, the pump of the present invention is applicable to the pumping of fluids other than liquids such as gases, as for 40 example air or mechanical refrigerants. When the device is used with oil as the hydraulic liquid, lubrication is automatically taken care of by the contact of the oil with working parts directly and by the normal unavoidable leakage of the oil 45 to working parts not directly in contact with the oil being pumped. When the device is used for pumping gas such as air, suitable lubrication of the working parts must be provided for.

50 Referring to the drawings in detail, reference numeral 1 designates the pump housing generally, this housing comprising a circular portion 2 which encases the rotor and associated parts and an end portion 3 integral therewith which encases the end of the shaft and the valving mechanism and which is provided integrally with the inlet

and outlet conduits through which the working liquid is supplied and removed. These conduits or passageways are designated as 4 and 5 and whether a given conduit 4 or 5 functions as suction or pressure side of the pump depends upon the direction of rotation of the rotor. For example, if the rotor is rotated in a direction clockwise of Figs. 2 and 3 the upper conduit 4 will function as the suction or inlet side while the lower conduit 5 will be supplied by the pump with fluid under pressure. In this description it will be assumed that the motor or other pump driving means drives the rotor in the clockwise direction as indicated by the arrow on Fig. 2. The outer ends of conduits 4 and 5 are threaded for coupling to suitable other conduits.

The rotor 6 is integrally carried on the pump shaft 7, which is journaled in an offset position relative to the center of the housing 1, being supported by the tapered roller bearings 8 and 9, bearing 8 being mounted in an end plate 10 which is fixedly attached to the housing portion 2 in any suitable manner (not shown). Left hand bearing 9 is likewise carried in the housing portion 3. These bearings 8 and 9 are oppositely directed.

Means is provided for taking up wear of bearings 8 and 9 by a single adjusting operation. This means takes the form of an adjusting member 11 screw-threadedly received in the left-hand end of the casing portion 3 and which abuts against the outer race 29 of bearing 9 and is adapted to push this outer race inwardly and thereby take up slack in bearing 9 and thence through the inner race 30 of bearing 9, through the valving sleeve 12 which is fixedly carried on shaft 7 which abuts against rotor 6, through the rotor 6, and through right hand side wall plate 13 which is fixedly carried on shaft 7 to the inner race 31 of bearing 8, thus taking up the slack in bearing 8 because its outer race 32 is fixedly held in end plate 10. Adjusting member 11 is provided with recesses 14 for receiving a spanner for rotating member 11. A detachable cap plate 15 may be carried in any suitable manner by casing portion 3 over the adjusting member 11.

Sleeve 12 has an integral flange which functions as a left hand side wall 16 which cooperates with right hand side wall 13 in a manner which will presently appear to seal the pumping chambers.

Sleeve 12 and right hand side wall 13 are fixedly carried by shaft 7 and rotor 6 in any suitable manner in close sealing relationship thereto, as illustrated in the drawings, by means of pins 17, or in any other manner as by shrinking thereupon.

The rotor 6 is provided with a plurality (four) of equally angularly spaced radial slots within which tightly but slidably are disposed rectangular vanes 18 which have a thickness only very slightly less than the thickness of their receiving slots. The receiving slots have a depth at least equal to the width of the vanes 18. The vanes 18 are just slightly less in length than the distance between side walls 13 and 16 so as to form a tight but slidable fit with the smooth inner faces of walls 13 and 16.

Surrounding rotor 6 and vanes 18 is the ring or cylinder 19 which is mounted rotatably as the inner race of a ball bearing having balls 20 around and rollingly engaging ring 19 and an outer race 21 which is rollingly engaged with and surrounds balls 20 and which is stationarily mounted in any manner within the casing por-

tion 2. Thus ring 19 rotates with rotor 6 and vanes 18, being drawn around at the same speed as rotor 6 by reason of the fact that the frictional force of engagement of vanes 18 with ring 19 is much greater than the sum of the rolling friction of ring 19 with balls 20 and the rolling friction of balls 20 with race 21. Thus ring 19 is held in eccentric relationship to the rotor 6 but is free to rotate therewith. Ring 19 is of a width only slightly less than the distance between side walls 13 and 16 so as to slidably but tightly engage with the inner faces thereof, thus allowing the necessary slight relative movement between ring 19 and side walls 13 and 16 as rotation of the rotor takes place.

As a result of the construction so far described, vanes 18 form with rotor 6, ring 19 and side walls 13 and 16 closed expanding and contracting chambers, the upper chamber in Fig. 2 expanding to draw in fluid and the lower chamber contracting to compress or exert pressure on the fluid. The horizontal intermediate chambers on each side of Fig. 2 exert substantially no pumping action and are sealed off while they are in the horizontal or substantially horizontal position in order to separate the pressure side of the pump from the inlet side and because they exert no pumping action as they pass through this position in which they are converted from suction to pressure chambers or vice versa. For example, the right-hand chamber in Fig. 2 is at a maximum volume and is undergoing a change from a suction to a pressure chamber whereas the left-hand chamber is at its minimum volume and is being converted from a pressure chamber to a suction chamber.

In order to valve the working chambers thus formed, rotor 6 is provided with ports 22 which lie intermediate the vanes and which extend radially inwardly and thence axially to the side of the rotor where they communicate with ports 23 extending axially in sleeve 12 and then radially outwardly to the periphery of sleeve 12.

The valving is carried out at the periphery of sleeve 12 adjacent the outlet of ports 23, in such manner as to connect the expanding upper chambers to the suction inlet 4 of the pump and to connect the contracting lower chambers to the pressure inlet 5 of the pump, and further to seal off the intermediate chambers when they pass through the horizontal position. For this purpose, housing portion 3 is formed internally around sleeve 12 with an upper annular arcuate space 24 and with a similar lower annular connecting space 25, these spaces being separated by the projections 26 and 27 at the right and left hand respectively. Projections 26 and 27 are so formed inwardly as to tightly but rotatably engage the surface of rotating sleeve 12 and are somewhat wider peripherally than the outlet of ports 23, so as to insure tight sealing thereof as they pass by.

Thus, as the pump is shown in the drawings, the right-hand working chamber in Fig. 2 is sealed off because its port 23 is passing projection 26 and the left-hand working chamber is sealed off because its connecting port 23 is passing projection 27. The upper suction chamber is freely connected to pump inlet 4 while the lower pressure chamber is likewise connected freely to the pump outlet 5.

To prevent undue leakage of oil along sleeve 12 when oil is the medium pumped and to provide an oil seal when gas is being pumped, a pair of oil grooves 28 are provided in the periphery of

sleeve 12, one on each side of the inlet 4 and outlet 5.

The operation of the pump will be obvious from the foregoing description and need not be set forth in its entirety at this point. It will be understood that the vanes 18 move radially outwardly under the influence of centrifugal force as the rotor 6 revolves, into engagement with ring 19 which they carry around with them. As ring 19 is thus carried around, a slight shifting movement thereof relative to the vanes occurs because of the eccentricity of the rotor and ring. The magnitude of the resulting slight friction is not to be compared, however, with the friction which would result were ring 19 held stationary. In addition, there will be a small amount of friction between vanes 18 and the side walls 13 and 16 as they move inwardly or outwardly to meet ring 19, but this friction is not comparable with the friction which exists in the ordinary vane pump between the vanes and the stationary side walls.

From the foregoing description, it will be apparent that the present invention provides a highly efficient constant delivery vane pump in which the sliding friction of the vanes on the ring and upon the side walls has been eliminated. The mechanism is simple and economical to construct and operates for long periods of time without undue necessity for adjustment or maintenance. When wear does occur in the shaft supporting bearings, it can readily be taken up by simple adjustment of the single adjusting member. It will further be seen that the pump of the present invention is adapted for advantageous porting and valving in such manner that the most efficient and effective operation results.

It will be seen from the foregoing description that the inner race or cylindrical ring 19 takes up the outward thrust of the vanes 18 due to centrifugal force and transmit this thrust to the outer race 21 and thence to the pump housing 1. It will further be seen that the inner ring 19 is positioned longitudinally by the side wall 13 and the porting sleeve 12 which carries side wall 16, the wall 13 and the sleeve 12 being positioned longitudinally by the bearings 8 and 9. As bearings 8 and 9 are adjusted by the member 11 the sleeve 12 and wall 13 are moved longitudinally to a slight extent. As this action takes place the ring 19 is similarly moved slightly longitudinally and carries the outer race 21 slightly longitudinally since race 21 is free to move longitudinally in housing portion 2, although it will be retained against rotation because its frictional engagement with the housing portion 2 is so much greater than the rolling friction of the ring 19 and rolling elements 20 with the outer race 21.

As is shown more clearly in the exaggerated view of Fig. 4 the bearings 8 and 9 support the sleeve 12 with clearance within the housing portion 3 such that leakage of fluid being pumped therealong is prevented and yet this sleeve 12 is slidable within this housing portion 3 and is free from binding therein even though a considerable force tending to cause binding be exerted by the pump mechanism; as for example, when pumping extremely viscous liquids which might generate forces of sufficient magnitude to cause binding between these parts.

Fig. 4 further illustrates the fact that there is no clearance between the sleeve 12 and the shaft 7 and the rotor 6 and that the clearance between the side walls 13 and 16 and the rotat-

ing ring 19 is substantially of zero magnitude. Fig. 4 further illustrates that there is considerable clearance between the outer race 21 and the housing portion 2, this clearance being greater than that provided between the sleeve 12 and the housing portion 3 because it is not necessary that the outer race 21 be fluid-tightly sealed with respect to the housing portion 2, it only being necessary that outer race 21 be free to move longitudinally upon adjustment of the pump bearings.

Fig. 4 further illustrates that the outer race of bearing 8 is very tightly engaged with the cover plate 10, that the inner races 31 and 30 of bearings 8 and 9 very tightly engage the surface of the shaft 7, and that the outer race 29 of bearing 9 has considerable clearance between it and the housing portion 3 so that it is free to move longitudinally during adjustment of the bearings to take up wear. The clearance between the outer race 29 and the housing portion 3 being somewhat smaller than that between sleeve 12 and housing portion 3, because it is not necessary or desirable that outer race 29 freely rotate, whereas, it is necessary that sleeve 12 be capable of freely rotating. The disposition of the bearings 8 and 9 at each end of the rotor prevents the binding which is usual in the ordinary pump in which the pintle is journaled on only one side. Moreover the shaft of the pump is accessible from both ends of the pump.

In my copending application, Serial No. 310,507, filed December 22, 1939, there is disclosed and claimed the generic inventive thought. In the present application, there is claimed the application of the generic inventive thought as applied to a constant delivery or displacement pump.

Having thus fully described my invention, what I claim as new and desire to secure by Letters Patent is:

1. A constant delivery pump comprising a freely rotatable ring, a rotor therewithin, means connected with said rotor and extending between said ring and said rotor for forming a plurality of working chambers therebetween, said means including vanes slidably engaging said ring and side walls connected to said rotor and slidable relative to said ring, cylindrical means rotating with said rotor and containing ports communicating with said chambers and extending to the periphery of said cylindrical means, angularly spaced arcuate collecting zones surrounding said cylindrical means and adapted to successively connect with each of said ports, and sealing means between said zones for sealing a portion of the periphery of said cylindrical means and for sealing at least one of said ports as it passes said sealing means.

2. In a pump, a pump housing comprising a pumping chamber and inlet and discharge passageways, a rotor slidably mounted in said housing transverse to said inlet and discharge passageways, said rotor having a plurality of radially disposed centrifugally operated pumping vanes freely mounted therein between ports in said rotor communicating with the pumping chamber and with said inlet and discharge passageways, a freely movable and laterally adjustable bearing assembly interposed between the interior of said casing and the exterior of said vanes in said pumping chamber and adapted to engage with and limit the outward movement of said vanes, bearing means at each end of said rotor, and means operable from the outside of the housing

for adjusting said bearing means so as to adjust said rotor and bearing means together with said bearing assembly transversely of said pump, said bearing means comprising opposed oppositely disposed tapered roller bearings the inner races of which are adapted to engage with the sides of said rotor as well as the rotor shaft.

3. In a pump, a casing having a pumping chamber and inlet and discharge passageways, a rotor having a shaft transversely arranged with respect to said casing, a plurality of centrifugally operated, freely movable vanes in said rotor, a bearing assembly surrounding said vanes between the ends thereof and the interior of said casing, a distribution sleeve mounted on said rotor adapted to control the inlet and exit of fluid from the pump in association with the rotor and rotating with it, means on each end of the shaft of said rotor comprising tapered roller bearings for supporting said rotor in said distribution sleeve, said tapered roller bearings being so arranged as to support said distribution sleeve in spaced relationship with respect to said casing, but so close thereto as to provide a substantially fluid-tight engagement without mechanical binding of said distribution sleeve with said casing.

4. In a pump, a casing having a pumping chamber and inlet and discharge passageways, a rotor including a shaft transversely arranged with respect to said casing, a plurality of centrifugally operated, freely movable vanes in said rotor, a bearing assembly surrounding said vanes between the ends thereof and the interior of said casing, a distribution sleeve rigidly connected with said rotor and adapted to control the inlet and exit of fluid from the pump in association with the rotor, means on each end of the shaft of said rotor comprising tapered roller bearings for supporting said rotor and said distribution sleeve, said tapered roller bearings being so arranged as to support said distribution sleeve in spaced relationship with respect to said casing, but so close thereto as to provide a substantially fluid-tight engagement without mechanical binding of said distribution sleeve with said casing, said tapered roller bearings, rotor, its bearing assembly, and distribution sleeve being capable of adjustment, and means for adjusting said tapered roller bearings to simultaneously adjust laterally said rotor, its bearing assembly and the distribution sleeve.

5. A vane pump comprising in combination a rotor, a plurality of radially disposed pumping vanes slidably mounted in said rotor, a pump casing including a fluid inlet and fluid outlet, an anti-friction bearing having its outer raceway mounted for adjustment in longitudinal direction of said casing while the inner race of said bearing is adapted to limit the outward movement of said vanes, and slightly to move relatively thereto, said rotor being adjustably mounted in said casing and having passageways adapted successively to communicate with said fluid inlet and outlet and being provided with flange portions movable independently of said inner race and forming therewith and with said rotor and vanes pressure and suction chambers respectively communicating with said passageways, adjustably mounted tapered roller bearings on each side of said flange portions for supporting the rotor, and adjusting means adjacent one of said roller bearings and adapted simultaneously to adjust said tapered roller bearings, said anti-friction bearing and said rotor.

6. In combination in a vane pump, a casing

having a fluid inlet and outlet, a rotor journalled at both ends in said casing and having radial passageways therein and also lateral passageways therein communicating with said radial passageways, a valve shaft surrounding a portion of said rotor and being rigidly connected thereto, said valve shaft being provided with radial

10 passageways continuously communicating with the lateral passageways in said rotor irrespective of the pressure in said pump and adapted alternately to communicate with said fluid inlet and outlet, means associated with said casing for controlling said alternating communication between said fluid inlet and outlet and said passageways in said valve shaft, a ring surrounding said rotor and being eccentrically positioned with respect thereto, a plurality of vanes slidably mounted in and extending outwardly from said rotor into frictional engagement with said ring, and a pair of spaced annular wall members rigidly connected to said valve shaft and said rotor, respectively, and confining with said rotor together with said vanes and said ring pressure and suction chambers continuously in hydraulic connection with said passageways in said rotor.

7. In combination in a vane pump, a casing having a fluid inlet and outlet, a rotor rotatable within said casing, anti-friction bearing means with an outer race longitudinally slideable in said casing and with an inner race spaced from but surrounding a portion of said rotor, a plurality of vanes reciprocably connected in said rotor and extending between said rotor and said inner race, spaced wall members rigidly connected to said rotor and confining with the latter together with the vanes and said inner race suction and pressure chambers, a plurality of passageways in said rotor for respectively connecting said suction and pressure chambers with said fluid inlet 30 and outlet, additional bearing means adjacent each end of said rotor for supporting said rotor in said casing said additional bearing means being adjustable for wear upon axial motion of a portion thereof, and means for adjusting said 35 rotor and said additional bearing means as a unit in longitudinal direction of said rotor to take up wear of said additional bearing means and to facilitate the assembly of said pump.

8. A constant delivery pump comprising a 40 rotor, a bearing encircling said rotor and comprising an inner and an outer race and rolling elements disposed therebetween, vanes extending between said rotor and said inner race, spaced wall members rigidly connected to said rotor and 45 forming therewith and with said vanes and said inner race chambers, a housing for said outer race, said housing having fluid inlet and outlet ports for said chambers, a valve including ported means associated with said rotor so as to rotate therewith for providing communication between 50 said chambers formed by said rotor, spaced wall members, vanes and inner race and said inlet and outlet ports, and means carried by said housing for valving said ported means.

9. A constant delivery pump comprising a 55 rotor, a bearing encircling said rotor and comprising an inner and an outer race and rolling elements disposed therebetween, spaced wall members rigidly connected to said rotor, a plurality of vanes extending between said rotor and 60 said inner race and forming suction and pressure chambers with said inner race, with said side walls and with said rotor, a housing for said outer race, a sleeve rotatable with said rotor, 65 said housing defining with said sleeve a pair of

spaced collecting spaces, said sleeve having passageways continuously communicating with said chambers and adapted to communicate with said collecting spaces, said passageways extending to the periphery of said sleeve, and means in sliding engagement with said sleeve for controlling fluid connection between said passageways and said collecting spaces.

10. In a pump, a pump housing comprising a pumping chamber and inlet and discharge passageways, a rotor slidably mounted in said housing transverse to said inlet and discharge passageways, said rotor having a plurality of radially disposed centrifugally operated pumping vanes freely mounted therein, ports in said rotor communicating with the pumping chamber and with said inlet and discharge passageways, said vanes located between said ports, a freely movable and laterally adjustable bearing assembly interposed between the interior of said casing and the exterior of said vanes in said pumping chamber and adapted to engage with and limit the outward movement of said vanes, oppositely directed tapered anti-friction bearings for supporting both ends of said rotor, the outer races of said anti-friction bearings being supported by said housing and the inner races of said anti-friction bearings being supported by said rotor, and means adjustable from the outside of said housing and engaging one of said anti-friction bearings for effecting adjustment of said anti-friction bearings as well as of said bearing assembly.

11. In combination in a vane pump, a casing having a fluid inlet and outlet, a rotor rotatable within said casing and having a plurality of vanes reciprocably mounted therein, antifriction bearings adjacent each end of said rotor for

5 supporting the same in said casing, a sleeve surrounding a portion of said rotor and being rigidly connected thereto, said sleeve being movable in said casing with a clearance greater than the clearance between the outer races of said bearings and the adjacent surface of said casing and having a plurality of radial passageways for alternately communicating with said inlet and outlet, spaced wall members fixedly connected to said rotor at each side thereof for rotation therewith, and an anti-friction bearing surrounding a portion of said rotor and having an inner race forming with said vanes, said rotor and said wall members a plurality of chambers communicating with said passageways.

10 12. In combination in a vane pump, a casing having a fluid inlet and outlet, a rotor rotatable within said casing, tapered roller bearings adjacent the ends of said rotor and located in said casing for supporting said rotor, a sleeve surrounding a portion of said rotor and being rigidly connected thereto, said sleeve being movable in said casing with a clearance greater than the clearance between the outer races of said roller bearings and the adjacent surface of said casing and having a plurality of radial passageways for alternately communicating with said inlet and outlet, a plurality of chambers located within the casing and radial vanes separating said chambers from each other, said chambers connected with said passageways, a pair of annular grooves on the periphery of said sleeve and respectively located on each side of said inlet and outlet, and adjusting means adjacent one of said bearings and operable to adjust both roller bearings as a unit.

35 WARREN R. TUCKER.
